UNITED STATES PATENT OFFICE.

PAUL DAIMLER, OF CANNSTATT, AND MAX FRIZ, OF UNTERTÜRKHEIM, GERMANY,
ASSIGNORS TO DAIMLER-MOTOREN-GESELLSCHAFT, OF UNTERTÜRKHEIM, GERMANY.

STARTING DEVICE FOR INTERNAL-COMBUSTION ENGINES.

1,136,512.

Specification of Letters Patent. Patented Apr. 20, 1915.

Application filed May 4, 1914. Serial No. 336,367.

To all whom it may concern:

Be it known that we, PAUL DAIMLER, a subject of the King of Wurttemberg, residing at Cannstatt, in the German Empire, and MAX FRIZ, a subject of the King of Wurttemberg, residing at Untertürkheim, near Stuttgart, in the German Empire have invented new and useful Improvements in Starting Devices for Internal-Combustion Engines, of which the following is a specification.

This invention relates to an improved device for starting internal combustion engines and adapted to enable the engine to be started in any position of the crank shaft without it being necessary to first of all bring the crank shaft into a certain position. The gas residues of all the cylinders not open to the exhaust are drawn off by the starting device in the known manner and fresh mixture supplied to the cylinders. One of the cylinders will always be in the expansion period of its cycle so that on actuating the starting magneto the first ignition will take place in this cylinder and thus set the crank shaft in motion. In immediate succession a further ignition will take place in the next cylinder which was previously stopped in the compression period of its cycle and the engine will thus be started.

According to the present invention each cylinder, in addition to having the usual admission and exhaust valves, is also provided with an eduction valve through which the gas residues in the cylinder can be withdrawn. A starting cam is provided on the cam shaft for each cylinder in addition to the usual admission and exhaust cams. The starting cams are adapted to be put into and out of operation as required and are so disposed relative to the admission and exhaust cams that they open the admission and eduction valves of those cylinders which are not open to exhaust in order to enable the gas residues in these cylinders to be withdrawn and enable a fresh gas mixture to enter, while the starting cams do not actuate the valves of those cylinders which are open to the exhaust. The gas residues in the cylinders are withdrawn through the eduction valves in the usual manner by means of a manually-operated pump.

In order that the admission valve which is opened simultaneously with the eduction valve by the starting cam on starting the

engine, may also be opened by the admission cam when the engine is running normally without at the same time opening the eduction valve, a clutch device is interposed between the lever mechanism of the admission valve and the lever mechanism of the eduction valve adapted to operate in one direction only.

In order that the invention may be more clearly understood reference is made to the accompanying drawings showing one embodiment of the invention by way of example.

Figure 1 is a diagrammatic view of an internal combustion engine fitted with the improved starting device. Fig. 2^a is an enlarged plan view of the starting mechanism. Figs. 2^b to 2^e are cross-sectional views on the line A B of Fig. 2^a showing the parts in the various positions they assume. Figs. 3 to 8 are diagrammatic views illustrating the functions of a six-cylinder motor when starting, the small superposed broken-line figures showing the position of the cams corresponding to the positions of the crank and connecting rod shown in the main figures by broken line. Fig. 3 shows the position of the parts during the expansion period. Fig. 4 shows the position near the end of the exhaust period; Fig. 5 at the end of the suction period; Fig. 6 at the end of the expansion stroke and commencement of exhaust; Fig. 7 during the compression period and Fig. 8 at the commencement of the suction stroke.

Each cylinder *a* in addition to having the usual admission valve *c* and exhaust valve (not shown) is also provided with an eduction valve *d* through which the gas residues in the cylinder can be withdrawn. The admission valve *c* and exhaust valve are operated in the usual manner by means of admission cams 1 and exhaust cams 2 mounted on the cam shaft *b* which also carries a starting cam 3 for operating the eduction valve *d*. The cam 3 coacts with a roller carried by a link *f* mounted on a crank lever *g*, *h*, whose arm *h* is connected to a lever *k* operating the eduction valve *d*. The hub *g'* of the crank lever *g*, *h* is mounted to rotate on a pin *e* on which the hub *m'* of a double-armed lever *m* is rotatably mounted, the lever *m* being operated by the admission cam 1 and connected to the admission valve *c*. The hubs *g'* and *m'* interlock as seen in Fig. 2^a.

Fig. 2^a but are capable of a certain amount of play between each other so that when the lever *m* is actuated by the admission cam it can operate the admission valve *c* without moving the lever *g*, *h* and consequently without opening the eduction valve *d* whereas the eduction valve *d* can be opened by the lever *g*, *h* when operated by the starting cam 3 if the admission valve *c* is already open, while finally the two valves *c* and *d* can be opened simultaneously by the starting cam 3.

The various positions of the interlocking hubs *g'* and *m'* are shown clearly in Figs. 2^b to 2^c. Fig. 2^b shows the position assumed when the admission valve *c'* and eduction valve *d* are closed. Fig. 2^c shows the position when the admission valve *c* is opened by the admission cam 1 while the eduction valve *d* remains closed, this being the case when the engine is running normally. It will be seen from Fig. 2^b that the hub *m'* of the lever *m* has been turned through an angle *x* which corresponds to the stroke of the valve *c*. Fig. 2^c shows the position which the hubs assume when the admission valve *c* is opened by the admission cam 1 and when the eduction valve *d* is opened by the starting cam 3. The hubs *g'* and *m'* assume the positions illustrated in Fig. 2^a when the admission valve *c* and eduction valve *d* are simultaneously opened by the starting cam 3.

Mounted above the link *f* is a shaft *n* carrying a switch lever *o* and having a depending arm *o'* which is connected to the link *f* by a bolt *o*. By turning the lever *o* into the position indicated by broken lines, the roller of the lever *f* is swung out clear of the starting cam 3 as indicated by the dotted circle. In the position illustrated in full lines in Fig. 1 the starting device is in operative position, the valves *c* and *d* being open so that the gas residues in the cylinder may be drawn off through the valve *d* by a manually operated pump connected to the connection *p*, while a fresh gas mixture is drawn in from the carburetor through the valve *c*.

As will be readily seen from Figs. 3-8 of the drawings the starting cam 3 is so disposed relatively to the admission cam 1 and exhaust cam 2 that it only actuates the valves *c* and *d* of those cylinders which are not open to the exhaust. Thus Figs. 4 and 6 show cylinders during their exhaust period when the valves *c* and *d* remain closed whereas Figs. 3, 5, 7 and 8 show cylinders during the expansion, compression or admission when the valves *c* and *d* are opened by the starting cam 3 so that in the position shown in Figs. 3, 5, 7 and 8 the gas residues in the cylinders will be withdrawn through the open eduction valve *d* while fresh mixture will be supplied to the cylinders from the carburetor through the open admission valves *c*.

ders from the carburetor through the open admission valves *c*.

Although the improved starting device has been illustrated and described as applied to an engine whose cam shaft is axially fixed 70 it will be readily understood that the device may be also applied to engines of the type in which the cam shaft is axially movable in which case the lever mechanism for operating the valves from the starting cam 3 75 may be dispensed with and the cam shaft provided with a transition device which enables the roller coacting with the admission cam to make contact with the starting cam.

A particular advantage of the improved 80 starting device is that the engine can be started in any position without manipulation by the driver thus insuring greater reliability.

We claim:

1. In combination with a multi-cylinder internal combustion engine having admission and exhaust valves for each cylinder, a starting device comprising an eduction valve for each cylinder through which the 90 gas residues may be withdrawn, and mechanism for simultaneously opening the admission and eduction valves of those cylinders whose exhaust valves are closed at the moment of starting the engine and for closing 95 the eduction valve of the cylinder whose exhaust valve is open at that moment.

2. In combination with an internal combustion engine having admission and exhaust valves operated from admission and 100 exhaust cams on a cam shaft, a starting device comprising an eduction valve, and a starting cam on said cam shaft so disposed relatively to said admission and exhaust cams that the admission and eduction valves 105 are opened when the exhaust valve is closed to enable the gas residues in the cylinders to be withdrawn and enable fresh gas mixture to enter the cylinder.

3. In combination with an internal com- 110 bustion engine having admission and exhaust valves operated from admission and exhaust cams on a cam shaft, a starting device comprising an eduction valve, a starting cam on said cam shaft, valve mechanism operated by said starting cam to open said admission and eduction valves, said cam being so disposed relatively to said admission and exhaust cams that the admission and eduction valves are opened when the exhaust 115 valve is closed to enable the gas residues in the cylinders to be withdrawn and enable fresh gas mixture to enter the cylinder and means for putting said valve mechanism into or out of coöperation with said starting cam. 12

4. In combination with an internal combustion engine having admission and exhaust valves, a cam shaft and admission and exhaust valves on said cam shaft adapted to operate said admission and exhaust valves, 13

a starting device comprising a starting cam on said cam shaft, a pivoted lever adapted to be operated by said starting cam, an eduction valve in the cylinder operated by said lever, an admission valve lever pivoted co-axially with the first mentioned lever and adapted to be operated by said admission cam and to operate said admission valve, said starting cam being so disposed relatively to said admission and exhaust cams and said co-axially pivoted levers being so interconnected that the admission and eduction valves may be opened by said starting cam when the exhaust valve is closed while said admission cam may open said admission valve without opening said admission and means for putting said eduction valve, lever into and out of coöperation with said starting cam.

5. In combination with an internal combustion engine having admission and exhaust valves, a cam shaft, admission, exhaust and starting cams on said cam shaft, mechanism for operating said exhaust valve

from said exhaust cam, co-axially pivoted 25 levers adapted to be operated by said starting and admission cams respectively, an eduction valve in said cylinder, mechanism for connecting said admission valve with the lever operated by the admission cam, mechanism for connecting said eduction valve 30 with the other lever, interlocking hubs on said levers admitting of slight play so that the lever connected with the admission valve may be operated without operating the other 35 lever while both levers may be operated by said starting cam, and a device for putting the lever connected with the eduction valve into or out of coöperation with said starting cam.

In witness whereof we have hereunto set our hands in the presence of two witnesses.

PAUL DAIMLER.
MAX FRIZ.
